(57) **CLAIM**

The ornamental design for an orb bait station as shown and described.

DESCRIPTION

FIG. 1 is a front perspective view showing the ornamental design of the claimed orb bait station;

FIG. 2 is an exploded and perspective view thereof;

FIG. 3 is a front view thereof;

FIG. 4 is a back side view thereof;

FIG. 5 is a left side view thereof;

FIG. 6 is a right side view thereof;

FIG. 7 is a top view thereof;

FIG. 8 is a bottom view thereof;

FIG. 9 is a perspective view of bait holder; and,

FIG. 10 is a top view of a bait holder.

In FIG. 8, the dash-dash broken lines are for the purpose of illustrating portions of the orb bait station that forms no part of the claimed design.
